UNITED STATES PATENT OFFICE.

WILLIAM J. CHENOWETH, OF DECATUR, ILLINOIS.

PUTTING CUP.

Application filed June 9, 1922. Serial No. 566,981.

To all whom it may concern:

Be it known that I, WILLIAM J. CHENOWETH, a citizen of the United States, a resident of Decatur, in the county of Macon and 5 State of Illinois, have invented new and useful Improvements in Putting Cups, of which the following is a specification.

This invention has reference to putting-cups used as linings for the putting-holes of 10 putting-greens of golf courses.

The invention has for its principal object to provide a cup of the character referred to which is self draining, thus eliminating the possibility of water and mud accumulat- 15 ing therein to soil the golf-balls or the hands of players removing balls played into the cups; also to provide a cup wherein certain of the drain openings may be used for the insertion of the fingers for the bodily re- 20 moval of the cup when it is desired to change the position of a cup, and also to provide a tapered sleeve disposed axially within the cup to receive the staff carrying the marker or flag, said sleeve also provided 25 with drain openings in its wall.

The invention has for a further object to provide a cup which may be cast in one piece, and embody the features above enumerated, thereby producing a cup at small 30 initial cost and being self contained no labor cost is required to assemble and parts may not become detached by rusting, or otherwise lost.

That my invention may be more fully understood reference is had to the accompanying drawings forming a part of the description, illustrating a preferred embodiment of the invention, in which:—

Figure 1 shows in elevation, partly in section, a putting-cup embodying my invention, and

Figure 2 is a top plan view of one half of the cup.

Like characters of references denote corresponding parts throughout the figures.

In the drawings 1 designates the cup comprising a cylinder or tube of a length and diameter adapted to fit in and form the lining for the ball receiving hole in the putting-green. Approximately midway between the ends of the cylinder is provided a partition or plate 2 which is preferably cast integral with the wall of the cylinder. A similar partition or plate 3, to that designated 2, is provided adjacent one end of the cylinder, preferably what is the lower end, and said

partition or plate, like the partition 2 is preferably cast integral with the wall of the cylinder. Disposed axially in the cylinder and between and connecting the partitions 2 and 3 and preferably cast integral therewith, is a tapered sleeve 4, open at both ends in the partitions, and the wall of said sleeve provided with openings 5 therein, preferably elongated slots, as shown. Said partitions 2 and 3 are also provided with openings 6 therein, preferably annularly arranged slots, as shown. The slots or openings 6 are also preferably superimposed, as shown.

I am aware that putting-cups, per se are not new and that their uses are well understood by those skilled in the art, but I am not aware of a cup so simple and possessing the characteristics of the one herein disclosed. The arrangement of the partitions 2 and 3 with the slots 6 provides not only a rigid support for the sleeve 4 which forms the bearing to support and maintain the marker staff A, but also provides for the proper and efficient draining of the cup. The opening at the upper end of the sleeve 4 in the partition 2 provides a seat for the golf ball dropping into the cup, and the slots or openings 6 in the partition 2 provide 85 grips for the insertion of the fingers and thumb to permit the easy withdrawal or removal of the cup from the hole when it is desired, as is often the case, to change the location of the hole in the green. The tapered sleeve, receiving a tapered staff insures the easy insertion of the staff therein and a wedging action due to the weight of the staff.

What I claim is:—

1. A putting cup made in one piece and comprising a cylindrical member formed with spaced annular partitions, one of such partitions being approximately centrally located and the other being located at or near the base of said member and both provided with an annular row of spaced drain openings, and an axially disposed marker staff receiving and aligning sleeve connecting said partitions, the arrangement of sleeve in its relation to said partitions and said member providing an uninterrupted space around said sleeve and between said partitions.

2. A putting cup made in one piece and comprising a cylindrical member formed 110 with spaced annular partitions, one of such partitions being approximately centrally lo-

cated and the other being located at or near the base of said member and both provided with an annular row of spaced drain openings, and an axially disposed tapered marker 5 sleeve connecting said partitions and provided with drain openings in its wall, the arrangement of sleeve in its relation to said

partitions and said member providing an uninterrupted space around said sleeve and between said partitions.

In witness whereof I have hereunto affixed my hand this 1st day of June, 1922.

WILLIAM J. CHENOWETH.
